UNITED STATES PATENT OFFICE.

JOHN F. REILLY, OF NEW YORK, N. Y.

APPARATUS FOR DISPOSING OF SNOW.

Application filed February 24, 1920. Serial No. 360,793.

To all whom it may concern:

Be it known that I, JOHN F. REILLY, a citizen of the United States, and residing at New York, in the county of New York and State of New York, have invented certain new and useful Improvements in Apparatus for Disposing of Snow, of which the following is a specification, such as will enable those skilled in the art to which it appertains to make and use the same.

This invention relates to apparatus designed to dispose of snow and similar matter from streets and roadways, and the object of the invention is to provide an apparatus of the class specified which is adapted to be detachably mounted in a sewer manhole in the street or roadway and suspended therein when in use; a further object being to provide means for placing the apparatus in communication with a water hydrant or other source of water supply, whereby a multiplicity of water sprays may be discharged from the apparatus into the manhole of the sewer while snow and similar matter is passed therethrough to break up the snow into small particles as well as to transform the snow into a slush which is carried off by the water flow in the sewer; and with these and other objects in view the invention consists in an apparatus of the class and for the purpose specified which is simple in construction and operation and efficient in use, and constructed and operated as hereinafter described and claimed.

The invention is fully disclosed in the following specification, of which the accompanying drawing forms a part, in which the separate parts of my improvement are designated by suitable reference characters in each of the views, and in which:

Fig. 1 is a diagrammatic sectional view indicating my improved apparatus and the method of its use;

Fig. 2 a partial transverse section on the line 2—2 of Fig. 1 and on an enlarged scale;

Fig. 3 a partial section on the line 3—3 of Fig. 1 and on an enlarged scale; and,

Fig. 4 a partial section on the line 4—4 of Fig. 1 and an enlarged scale.

In the accompanying drawing I have indicated at 5 a part of a street or roadway, and at 6 a manhole communicating with the sewer passage 7 at the bottom thereof which is located beneath the street 5. At 8 I have

shown in Fig. 1 a water hydrant in connection with which my improved apparatus operates. In practice, I provide a cylinder 9, the top of which is provided with an outwardly directed flange 10 which rests upon the street or roadway 5 in the manner illustrated in Fig. 1. The cylinder 9 is open at the top and bottom. Hinged to the bottom of the cylinder 9 as shown at 11 is a closure device 12 composed of openwork material 13 and pivoted to the cylinder 9 at the bottom thereof and opposite the hinge 11 of the device 12 is a pawl 14, the lower end of which is provided with a hook-shaped projection 15 adapted to engage the bottom portion of the device 12 to normally hold it in the position shown in Fig. 4, and the upper end of the pawl 14 is provided with a projecting arm 16 with which a cable, chain or the like 17 is connected, which cable passes upwardly through the manhole 6 and through the flange 10 and may be manipulated from the street 5. Another cable, chain or the like 18 is connected with the device 12 to permit of the closing of said device from the street level whenever desired, and as hereinafter described.

Mounted in the cylinder 9 at the upper end portion thereof is a pipe 19 which is approximately circular in form as shown in Fig. 2, and connected with this pipe is an upwardly directed pipe 20 at the upper end of which is a coupling 21 with which a flexible hose 22 is adapted to be connected, which hose also connects with the hydrant 8 as shown at 23.

A plurality of downwardly directed pipes 24, five of which are shown in the accompanying drawing, are connected with the pipe 19, as illustrated in Figs. 1 and 2 of the drawing, and the pipes 24 are each provided with a plurality of spaced discharged apertures 25, which form nozzles through which the water from the hydrant 8 passes into the cylinder 9, the lower ends of the pipes 24 are closed as shown at 26 by suitable caps or otherwise.

It will be noted on a consideration of Fig. 3 of the drawing that the apertures 25 in the pipes 24 are directed toward the center of the cylinder 9, or toward a common center and as the snow or similar matter passes into the cylinder from the street 5, a plurality of sprays of water are mixed with the snow and the pressure or force of these sprays will be

such as to break up the snow into small particles and transfer the same into a slush-like substance, which substance drops onto and passes through the openwork closure device 12.

It will be apparent that the openwork closure device will be constructed of comparatively strong material to withstand the weight of the snow or similar substance, and the mesh thereof will be of such size as to permit of the passage of comparatively large bodies of snow or slush therethrough. If at any time ice or frozen snow is dropped into the cylinder and will tend to clog the passage through the closure device, said closure device may be dropped by releasing the pawl 14 by an upward pull on the cable 17, and after the ice or frozen snow is dropped through the cylinder, the closure device may be again closed by pulling upwardly on the cable 18, and this device will be automatically locked in position by the pawl 14.

With my improved apparatus, it will be apparent that snow and similar matter may be quickly disposed of through the cylinder and sewer system of a street or roadway, or as quickly as the snow can be removed from the street or roadway and passed into the cylinder 9 by a number of workmen.

It is a well known fact that snow has heretofore been discharged into the manholes of sewers and in some cases effectively carried off depending largely upon the state or character of the snow, but it has also been experienced on numerous occasions that the snow will collect in the manhole of the sewer and will not be carried off by the flow of water in the sewer, but by mounting my improved apparatus in the manhole of a sewer snow in any state can be broken up and carried off by the flow of water in the sewer due to the transformation of such snow into a slush or melted snow. It will be understood on a consideration of Figs. 2 and 3 of the drawing that one side wall of the cylinder 9 is flattened as shown at 27 and the pipe 19 is fashioned to conform with the cylinder 9, and the object of this construction is to clear certain projections now employed in the manhole of the sewer.

It will also be apparent that by reason of the simplicity of the construction of my improved apparatus, the same may be readily placed in and detached from the manhole and, in the operation of clearing a street or other roadway, the apparatus will be carried along and placed in the successive manholes of the street or roadway, in the progress of clearing the snow from the street or roadway, and while I have shown certain details of construction for carrying my invention into effect, it will be understood that I am not necessarily limited to these details, and various changes therein and modifications thereof may be made, within the scope

of the appended claims, without departing from the spirit of my invention or sacrificing its advantages.

Having fully described my invention, what I claim as new and desire to secure by Letters Patent, is:—

1. An apparatus of the class described for use in connection with the manholes of sewers, comprising a horizontally arranged piping, a plurality of depending pipes connected therewith and adapted to extend downwardly into a manhole adjacent to the walls thereof, said horizontal piping and depending pipes being adapted to be detachably mounted in a manhole, means for supplying water to said horizontal piping, and means for discharging a plurality of sprays of water from each of said pipes into the central portion of the manhole. 75

2. An apparatus of the class described comprising a cylinder, a pipe mounted in the upper end portion of said cylinder, means for supplying water to said pipe, means for discharging a plurality of sprays of water radially into said cylinder, said cylinder being open at the top and bottom, and an openwork closure device hinged to the bottom of said cylinder. 80

3. An apparatus of the class described comprising a cylinder, a pipe mounted in the upper end portion of said cylinder, means for supplying water to said pipe, means for discharging a plurality of sprays of water radially into said cylinder, said cylinder being open at the top and bottom, 90 an openwork closure device hinged to the bottom of said cylinder, and a catch device for normally holding said closure device in its operative position. 100

4. An apparatus of the class described comprising a cylinder, a pipe mounted in the upper end portion of said cylinder, means for supplying water to said pipe, means for discharging a plurality of sprays of water radially into said cylinder, said cylinder being open at the top and bottom, an openwork closure device hinged to the bottom of said cylinder, a catch device for normally holding said closure device in its operative position, and means whereby said catch device may be released from said closure device. 105

5. An apparatus of the class described comprising a cylinder, a pipe mounted in the upper end portion thereof, means for supplying water to said pipe, and a plurality of pipes connected with and communicating with said first named pipe and extending downwardly into said cylinder, said last named pipes being each provided with a plurality of discharge apertures spaced longitudinally thereof and through which water from said first named pipe is adapted to pass radially into the cylinder. 125

6. An apparatus of the class described

comprising a cylinder, a pipe mounted in the upper end portion thereof, means for supplying water to said pipe, a plurality of pipes connected with and communicating with said first named pipe and extending downwardly into said cylinder, said last named pipes being each provided with a plurality of discharge apertures spaced longitudinally thereof and through which water

5 from said first named pipe is adapted to pass radially into the cylinder, the top of the cylinder being provided with an outwardly directed flange, and an openwork closure device hinged to the bottom of said

10 cylinder.

7. An apparatus of the class described comprising a cylinder, a pipe mounted in the upper end portion thereof, means for supplying water to said pipe, a plurality of pipes connected with and communicating with said first named pipe and extending downwardly into said cylinder, said last named pipes being each provided with a plurality of discharge apertures spaced longitudinally thereof and through which water from said first named pipe is adapted to pass radially into the cylinder, the top of the cylinder being provided with an outwardly directed flange, an openwork closure device hinged to the bottom of said cylinder, and a catch device cooperating with said closure device and adapted to normally hold the same in a closed position.

20

25

30

8. An apparatus of the class described comprising a cylinder, a pipe mounted in the upper end portion thereof, means for sup-

plying water to said pipe, a plurality of pipes connected with and communicating with said first named pipe and extending downwardly into cylinder, said last named pipes being each provided with a plurality of discharge apertures spaced longitudinally thereof and through which water from said first named pipe is adapted to pass radially into the cylinder, the top of the cylinder being provided with an outwardly directed flange, an openwork closure device hinged to the bottom of said cylinder, a catch device cooperating with said closure device and adapted to normally hold the same in a closed position, and means whereby said catch device may be released from the closure device.

9. An apparatus of the class described for use in connection with the man holes of sewers comprising a horizontally arranged tubular member and a plurality of depending tubular members in communication with said first named tubular member, means for supplying water to said first named tubular members, and means for discharging a plurality of sprays of water inwardly and radially from said last named tubular members.

In testimony that I claim the foregoing as my invention I have signed my name in presence of the subscribing witnesses this 21st day of February, 1920.

JOHN F. REILLY.
